UNITED STATES PATENT OFFICE.

ALEXANDER D. SCULLY, OF NEW YORK, N. Y.

UNIVERSAL SNAP-FASTENER BUTTON.

Application filed March 9, 1923. Serial No. 623,625.

To all whom it may concern:

Be it known that I, ALEXANDER D. SCULLY, a citizen of the United States, residing at New York, in the county of New York and State of New York, have invented certain new and useful Improvements in Universal Snap-Fastener Buttons, of which the following is a specification.

This invention relates to button clasps, and the main object is to provide a device which may be readily used as a cuff button or for automobile side curtains, or analogous purposes, the same being designed to releasably interlock both members.

Another object is to provide a button clasp composed of two members which are identically similar to each other, each having means thereon for interlocking both members to each other in a releasable manner by urging both members toward each other.

These and other objects will become apparent in the description below, in which characters of reference refer to like-named parts in the drawing.

Referring briefly to the drawing, Figure 1 is a sectional elevational view taken substantially centrally thru a pair of interlocked cuff buttons.

Figure 2 is a top plan view of one of the button members, showing the method of giving resiliency to the same.

Figure 3 is a sectional elevational view similar to Figure 1, taken thru a modified form of button clasp.

Figure 4 is a top plan view of one of the modified type of button members.

Referring in detail to the drawing, the numeral 10 indicates the outer keeper flange which is separated from the main body flange 11 by a stem 12, said stem being adapted to be inserted into the button hole of a cuff or other article. Flange 11 is annular and of relatively large diameter and has an annular cup shaped member 13 secured thereto, whose wall 14 is curved semicircularly. The bottom of the cup member is preferably permanently secured to said flange 11. The wall 14 of the cup is provided with a plurality of spaced apart slits 15 which render said wall particularly resilient. A second cup member is permanently fixed in the larger cup by securing the bottom 16 of the former to the bottom of member 13. The wall 17 of this cup is annular and curves divergently outward, the

largest diameter being at the upper edge. The channel 18 between the inner and outer cup members has a pair of studs 19 and 20 projecting upwardly from the bottom of the larger cup member, to which they are secured, and are surmounted by spherical heads 21. Said studs are preferably aligned diametrically opposite each other, the heads 21 thereof projecting somewhat above the upper edges of the cup members. The smaller cup member is also provided with a plurality of slits 22, the purpose therefore being the same as mentioned for the larger cup.

The modified type of clasp button shown in Figures 3 and 4 is of similar design to the preferred form, but the outer cups are shaped somewhat differently. The outer cup 23 is permanently mounted on an annular flat plate 24 which has a plurality of elongated holes 25 therein, which provide means for securing the device to an article of apparel or the like. Clips or stitches may pass thru said holes for the purpose described.

The encircling wall of the larger cup is tapered outwardly, the upper edge 26 being curved inwardly to form a hooked edge. Said outer cup is provided with a plurality of radial slits 27 for the purpose of resiliency. A sleeve 28 is mounted within the cup, its upper edge being divergently curved toward the hooked edge 26 of the outer cup member. Said sleeve also has its wall slotted at various places, as shown. A pair of studs 29 having knob heads 30 are connected by a cross bar 31 and rise vertically from the channel 32 formed between the outer cup and sleeve members, the bar of the studs being permanently fixed to the bottom of the sleeve.

The device is used in pairs only, that is, it takes two members to provide a complete clasp button. When two members are to be interlocked, the same are brought together, so that the spherical heads 21 of one member face the channel 18 of the opposite member. Both members are then urged toward each other. As the heads bear down upon the cup members, the wall segments thereof will give way, spreading in opposite directions and permitting said heads to enter into the channel 18 beneath the curved edges of the cup, wherein they are releasably retained in interlocked relation. In this manner a double locking is accomplished as each button member carries a

pair of stems, the heads of which engage the cup edges of the opposite member. The button members when interlocked may be readily separated by pulling the same away 5 from each other.

Another feature which is apparent is that my locking members provide a much greater wearing surface than those now in common use, and they interlock when brought together 10 in any position on their peripheries, thus eliminating the necessity of rotating one with respect to the other, as is necessary in many present types, to align the opposite interlocking parts.

15 I claim:

1. A separable fastener comprising a pair of members, an annular cup on each member having a plurality of slits therein, and means on said cups for interlocking a pair 20 of cups.

2. A separable fastener comprising a pair of flanged members, an annular cup on each of said members, the walls of said cups being inwardly curved at their upper edges, 25 and means on each member for releasably interlocking the lips of the opposite cup members.

3. A separable fastener comprising a pair of flanged members, an annular cup on each 30 member, a divergently tapered wall on said cup, the upper edge of said wall being

curved inwardly to form a hook, studs rising from the bottom of the cup, and means on the ends of said studs for engaging the curved wall of the opposite member. 35

4. A separable fastener comprising a pair of annular cup members, the upper edges of said cups being inwardly curved, the walls of said cups having slits therein, stems rising from each cup, and means for interlocking said cup members comprising spherical heads on the stems projecting above the cup members adapted to engage the inwardly-curved edge of the opposite member. 40

5. A separable fastener comprising a pair of annular cupped members, walls thereon, the upper edges of said walls being inwardly curved, a smaller cup member in each first-named cup having walls whose 50 upper edges are turned outwardly, the walls of all cup members being slotted to form resilient segments, stems rising from the bottom of the larger cup members having heads thereon, said heads of one member being adapted to be releasably retained between the larger and smaller cup members of the opposite members. 55

In testimony whereof I, affix my signature.

ALEXANDER D. SCULLY.
